UNITED STATES PATENT OFFICE.

ROBERT J. BENNETT, OF MOLINE, ILLINOIS, ASSIGNOR TO ARTISTA PIANO PLAYER COMPANY, OF MILAN, ILLINOIS, A CORPORATION OF ILLINOIS.

FOLDING TREADLE FOR PIANO-PLAYING ATTACHMENTS.

984,528.

Specification of Letters Patent.

Patented Feb. 21, 1911.

Application filed October 27, 1909. Serial No. 524,888.

To all whom it may concern:

Be it known that I, ROBERT J. BENNETT, a citizen of the United States, residing at Moline, in the county of Rock Island and 5 State of Illinois, have invented certain new and useful Improvements in Folding Treadles for Piano-Playing Attachments, of which the following is a specification.

This invention relates to improvements in 10 folding treadles for piano playing attachments, and the primary object of the same is to provide improved treadles which are adapted to be folded within the casing through an opening therein when not in use.

15 A further object is to provide improved treadles for operating the wind inducing bellows, and improved means for supporting the treadles whereby the wind inducing bellows may be located to the side of and at 20 points remote from the treadles and the treadles themselves located in such positions to permit ready access to the piano pedals, while at the same time the strings of the instrument which are located in the 25 base of the instrument are exposed to permit ready access thereto without dismantling the treadle mechanism.

30 A further object is to provide an improved treadle support and improved connections between the treadles and the operating mechanism for the wind inducing bellows which will permit the treadles to be readily folded into and unfolded out of the casing.

35 A further object is to provide an improved mechanism of this character which will be simple, durable and cheap in construction and effective and efficient in operation.

To the attainment of these ends and the 40 accomplishment of other new and useful objects as will appear, the invention consists in the features of novelty in the construction, combination and arrangement of the several parts hereinafter more fully described and claimed and shown in the accompanying drawings illustrating the embodiment of the invention, and in which—

45 Figure 1 is a detail elevation of the base of a musical instrument having a treadle attachment applied thereto constructed in accordance with the principles of this invention. Fig. 2 is an enlarged detail top plan view of the treadle mechanism. Fig. 3 is a detail end elevation with the end of the casing removed, showing the mechanism 50 in an operative position. Fig. 4 is a view

similar to Fig. 2, showing the mechanism folded inside of the casing. Fig. 5 is a view similar to Fig. 3 of a modified form of the invention. Fig. 6 is an enlarged detail view taken on line 6, 6 of Fig. 7. Fig. 7 60 is a detail top plan view of the operating arm, showing the manner of imparting movement from the arm to the operating mechanism of the wind inducing bellows.

Referring more particularly to the drawings and in the present exemplification of the invention, the numeral 10 designates a portion of the instrument to which this improved attachment is applied, and the casing is provided with an open front adjacent 65 the bottom. Within the casing and adjacent each side thereof and remote from the extremity 11 of the strings, which latter extend into the base and so as not to form an obstruction in front of the strings, are located two pumpers or suction-creating devices 12 in the form of pneumatics or bellows. Each of these bellows 12 is secured in 70 position in any suitable manner, preferably by means of a support 13, to which one of the members of the bellows is secured, preferably the front member, and the bellows 12 are arranged so that the movable member 75 thereof will be disposed toward the rear of the instrument and in a position to swing 80 in an upright plane. An elastic member 14 is arranged between the movable member 15 of the bellows and the rear wall 16 of the casing, which tends normally to collapse the 85 bellows.

90 Suitable spaced bearings 17 are provided and are arranged in pairs, each pair being connected by a base 18, which latter is secured to the bottom of the casing 10. Journaled in these bearings are shafts 19, one 95 of which shafts is provided for each of the bellows or pumpers 12. These shafts 19 are spaced longitudinally from each other, and secured to one extremity of each of the shafts is a crank arm 20, journaled to each 100 of which is a suitable anti-friction roller 21. Secured to the movable member 15 of the bellows 12 and extending beyond the edge thereof is a projection 22, preferably in the form of a plate, the free extremity of which 105 projects below the shaft 19 and curves toward the front of the casing, as shown more clearly in Fig. 3. The extremity of this plate or projection 22 terminates adjacent the anti-friction roller 21, so that when the 110

shaft 19 is rocked in a manner to be set forth to move the crank arm 20 toward the rear of the casing, the anti-friction roller 21 will force the projection 22 and the movable member 15 of the bellows 12 toward the rear of the casing to expand the bellows against the tension of the elastic member 14. Secured to the other extremity of each of the shafts 19 is a similar crank arm 23, which preferably projects toward the rear of the casing and at an angle to the arm 20.

A pair of members designated generally by the reference numeral 24 are provided, and one extremity of each of the members is deflected laterally as at 25, and these extremities 25 are journaled in suitable bearings 26 mounted upon suitable supports 27 within the casing. The end of the member adjacent the extremity 25 is deflected as at 28 to extend upwardly for any desired distance when the member is in the position shown in Fig. 3. The body of the member beyond the deflected positions 28 is then deflected or bent forwardly as at 29 to extend across and project beyond the end portion of the member and the deflected portion 29 is then deflected downwardly as at 31 and toward the toe-rail 30 to a point below the base of the casing, and the free end of the member is then deflected forwardly at an angle to the portion 31 for any desired distance, and at the free extremity of each of the members is secured a suitable support 32. These members 24 are spaced from each other and their free extremities are connected by means of a bar or rod 33, so that the members 24 and the connecting bar 33 form a support for the treadles 34. The forward extremity of each of these treadles is pivotally connected as at 35 to the member 33. Secured to and projecting beyond the rear extremity of each of the treadles is an extension 36 and a link 37 is connected by one extremity to the free extremity of the extension 36 as at 38, and by its other extremity to an arm 39 as at 40. The arm 39 is pivotally connected to the respective crank arm 23 as at 41, and the point of pivotal connection 41 of the arm 39 with the crank arm 23 is arranged in a direct line with the pivot formed by the deflected end 25 of the adjacent side member 24 with the bearing 26. A portion of the arm 39 when in operative position extends over the crank arm 23, and is provided with an abutting face 42 which engages and rests upon the adjacent portion of the crank arm 23, so that when the arm 39 is in an operative position as shown in Fig. 3, the face 42 will engage the arm 23 and form a practically rigid connection between the arm and the rock shaft 19. When the treadle is depressed from the position shown in Fig. 3, the link 37 will draw up the arm 39, which in turn will raise the rock arm 23 to rock the shaft 19 to move the crank 20 toward the

rear of the casing to expand the bellows. As soon as pressure is relieved from the treadle 34, the elastic member 14 will force the movable member 15 of the bellows 12 toward the fixed member of the bellows to collapse the bellows and at the same time the projection 22 will force the crank arm 20 in the opposite direction to lower the crank arm 23 and raise the free extremity of the arm 39, together with the end of the treadle 34 which is connected to the arm 39.

The side members 24 of the treadle support may be arranged in any suitable position, and the treadles 34 are spaced from each other a suitable distance to permit the 80 pedals 43 of the piano to extend into the space between the treadles so that the operator may have free and ready access to the 85 pedals 43 when desired. By providing the side members 24 with an arch-shaped extremity as shown, it will be apparent that the necessity for cutting slots or openings in the toe-rail 30 will be obviated, and when the treadles are moved to an unfolded or an operative position, the arch-shaped extremity of the side members of the treadle support will extend over the toe-rail. If desired, each of the side members may be provided with an enlarged portion or projection 90 95 44 arranged in a suitable position so as to engage the outer face of the toe-rail to steady and hold the arms or side members in position.

When not in use the treadles may be folded into the bottom of the casing through the 100 front thereof, and as the treadles and supports are raised, the side members 24 will move about the pivots formed by the extremities 25 thereof and the bearings 26, and these bearings being in direct lines with the 105 pivots 41 of the arms 39 with the respective crank arms 23, the arms 39 will move about their pivots to permit the treadles and side members of the supporting frame to fold within the casing. During this folding 110 movement the arm 39 will move about its point of pivotal connection with the crank arm 23, so as to move the abutting face 42 out of contact with the crank arm 23, and the treadle 34 will be moved about its pivot 115 35 so as to stand in close proximity to the portion of the side arms or members 24 in advance of the deflected portion 31, thereby allowing the parts to be compactly folded within the casing.

When it is desired to use the treadles, all that is necessary is to swing the side members 24 of the supporting frame about their pivots 25, and as the side members move into positions for use, the arm 39 will be moved 125 about its pivot 41 until the face 42 thereof contacts with the crank arm 23, in which position the rear extremities of the treadles 34 will be elevated to positions for use.

In the modified form of the invention 130

shown in Figs. 5, 6 and 7, the rock shafts 19 are provided with crank arms 44, which latter are substituted for the crank arms 23, and these arms 44 are each provided with 5 a lateral projection 45 adjacent its free extremity. In this form of the invention one arm 46 corresponding to the arm 38 is employed, and this arm 46 is loosely mounted intermediate its ends upon the rock shafts 10 19 for independent movement with respect thereto. The extremity 47 of the arm 46 projects below the rock shaft 19 and extends below the projection 45 on the crank arm 44. The free extremity of the arm 46 is adapted 15 to project beyond the front of the casing in a manner similar to the arm 39, and this free extremity is connected by means of a link 48 with the treadles 34. In this form of the invention and when the treadles are unfolded 20 to a position for use as shown in Fig. 5, the extremity 47 of the arms 46 will engage the projections 45 on the arms 44, so that when the treadles are depressed the arms 46 will be rocked about the shafts 25 19 as fulcrums and the extremity 47 will engage the lateral projection 45 on the arms 44 to raise the arms and thereby rock the shafts 19 in one direction to expand the bellows in a manner similar to the form of the 30 invention shown in Figs. 1 and 4. When pressure is released from the treadles, the bellows will be collapsed and the crank arms 44 will be depressed when the shaft 19 is rocked in the opposite direction. When 35 the arms 44 are depressed, the projections 45 thereon will depress the extremities 47 of the arms 46 to move the arms 46 about their pivots to position the treadles 34 for use. When the treadles 34 are folded into the 40 frame, the side members of the supporting frame will move about their pivots in the manner as already described. As the treadles are folded, the arms 46 will move about their pivots on the shaft 19 to cause the extremities 45 thereof to move away from the 45 projections 45 on the arms 44, and the free extremities of the arms 46 will then be moved into and project toward the rear 50 of the casing 10 to the position shown in dotted lines in Fig. 5. When the treadles are unfolded, the movement of the parts is reversed, and by the time the supporting feet 32 of the treadle supporting frame reaches the floor, the extremities 47 of the 55 arms 46 will be moved into engagement with the projections 45 upon the crank arms 44.

In order that the invention might be fully understood, the details of the foregoing embodiments thereof have been thus specifically described, but

What is claimed as new is—

1. In a folding pedal mechanism, the combination of a treadle support pivoted at its inner end to a stationary support, a rock 60 shaft, a bellows, an operative connection be-

tween the bellows and the shaft, a treadle pivoted at its forward end to the treadle support, a crank arm on the shaft, an operating arm disposed between the treadle and shaft, a link connecting the free end of 70 the treadle and the operating arm and an operative connection between the last said arm and the crank arm, said operating arm being shiftable with respect to its point of operative connection with the crank arm 75 during the folding and unfolding movements of the treadle.

2. In a folding pedal mechanism, the combination of a treadle support pivoted at its inner end to a stationary support, a rock 80 shaft, a bellows, an operative connection between the bellows and the shaft, a treadle pivoted at its forward end to the treadle support, a crank arm on the shaft, an operating arm disposed between the treadle and shaft, a link connecting the free end of the treadle and the operating arm and an operative connection between the last said arm and the crank arm, said operating arm being shiftable with respect to its point of 85 operative connection with the crank arm during the folding and unfolding movements of the treadle, the point of operative connection of the said operating arm with the crank arm being located in the same 90 horizontal plane with the pivot point of the treadle support.

3. In a folding pedal mechanism, the combination of a treadle support pivoted at its inner end to a stationary support, a rock 100 shaft, a bellows, an operative connection between the shaft and the bellows, a treadle pivoted at one end to the treadle support, a crank arm on the shaft, a pivotally supported operating arm disposed between the treadle and the shaft and operatively connected with the crank arm, and a link connecting the treadle with the operating arm, a portion of said operating arm beyond the pivot 105 abutting the said crank arm, the abutting portions of the said arms being movable out of engagement with each other during the folding movement of the treadle.

4. In a folding pedal mechanism, the combination of a treadle support pivoted at its 115 inner end to a stationary support, a rock shaft, a bellows, an operative connection between the shaft and the bellows, a treadle pivoted at one end to the treadle support, a crank arm on the shaft, a pivotally supported operating arm disposed between the treadle and the shaft and operatively connected with the crank arm, and a link connecting the treadle with the operating arm, a portion of said operating arm beyond the 120 pivot abutting the said crank arm, the abutting portions of the said arms being movable out of engagement with each other during the folding movement of the treadle, the point of operative connection of the said 125

arms being disposed in the same horizontal plane with the pivot point of the treadle support.

5. In a folding pedal mechanism, the combination of a treadle support pivoted at its inner end to a stationary support, a rock shaft, a bellows, an operative connection between the shaft and the bellows, a treadle pivoted at one end to the treadle support, a 10 crank arm on the shaft, an operating arm disposed between the treadle and the crank arm and pivotally connected by one end to the crank arm, and a link connecting the other end of the operating arm with the 15 treadle, said operating arm and the treadle support being co-axially mounted.

6. In a folding pedal mechanism, the combination of a treadle support pivoted at its inner end to a stationary support, a rock 20 shaft, a bellows, an operative connection between the shaft and the bellows, a treadle pivoted at one end to the treadle support, a crank arm on the shaft, an operating arm disposed between the treadle and the crank 25 arm and pivotally connected by one end to the crank arm, and a link connecting the other end of the operating arm with the treadle, said operating arm and the treadle support being co-axially mounted, a portion 30 of the operating arm beyond its pivot abutting the crank arm to form a rigid connection and movable cut of engagement with the crank arm during the folding movement of the treadle.

7. In a folding pedal mechanism the combination of a supporting frame comprising spaced side members pivoted at their inner ends to stationary supports, treadles pivoted by one end to the said frame, rock shafts 40 spaced longitudinally from each other, cranks on the adjacent ends of the shafts, an arm operatively connected to each of the cranks, the points of operative connection of the arms with the cranks and the pivots 45 of the said side members being located in the same horizontal plane, bellows disposed one on each side of the treadle supporting frame, operative connections between the shafts and the respective bellows, and links 50 connecting the free ends of the treadles with the respective arms, said arms being shiftable with respect to their points of operative connections with the cranks of the respective shafts during the folding and unfolding movements of the treadles.

8. In a folding pedal mechanism, the combination of a supporting frame comprising spaced side members pivoted at their inner ends to stationary supports, treadles pivoted by one end to the said frame, rock 60 shafts spaced longitudinally from each other, cranks on the adjacent ends of the shafts, an arm operatively connected to each of the cranks, the points of operative connection of the arms with the cranks and the

pivots of the said side members being located in the same horizontal plane, bellows disposed one on each side of the treadle supporting frame, operative connections between the shafts and the respective bellows, and links connecting the free ends of the treadles with the respective arms, said arms being shiftable with respect to their points of operative connections with the cranks of the respective shafts during the folding and unfolding movements of the treadles, portions of the operating arms abutting the respective crank arms to form rigid connections and being movable cut of engagement therewith during the folding movement of the treadles and supporting frame. 70

9. In a folding pedal mechanism, the combination of a treadle support pivoted at its inner end to a stationary support and being provided with an arched portion adapted to extend over the toe rail of a musical instrument, a rock shaft, a bellows, an operative connection between the shaft and bellows, a treadle pivoted to its support, an operating arm disposed between the shaft and the treadle, a link connecting the treadle and the arm, a crank arm on the shaft, and an operative connection between the crank arm and the first said arm, said connection and the pivot point of the treadle support being 95 disposed in the same horizontal plane.

10. In a folding pedal mechanism, the combination of a treadle support pivoted at its inner end to a stationary support and being provided with an arched portion adapted to extend over the toe rail of a musical instrument, said support having a bearing against the outer face of the instrument casting, a rock shaft, a bellows, an operative connection between the shaft and bellows, a treadle pivoted to its support, an operating arm disposed between the shaft and the treadle, a link connecting the treadle and the arm, a crank arm on the shaft, and an operative connection between the crank arm and the first said arm, said connection and the pivot point of the treadle support being disposed in the same horizontal plane. 100

11. In a folding pedal mechanism, the combination of a treadle support pivoted at its inner end to a stationary support and being provided with an arched portion adapted to extend over the toe rail of a musical instrument, a rock shaft, a bellows, an operative connection between the shaft and bellows, a treadle pivoted to its support, an operating arm disposed between the treadle and shaft, a crank arm on the shaft to which one end of the operating arm is pivotally connected, and a link connecting the other end of the arm and the treadle, the point of pivotal connection of said arms being co-axial with the pivot of the treadle support, and a portion of the operating arm beyond said pivot abutting the crank arm and mov- 120

able out of engagement therewith when the treadle support is folded.

12. In a folding pedal mechanism, the combination of a pedal support comprising 5 spaced side members pivoted at their inner ends to stationary supports, said side members being provided with arched portions adapted to extend over the toe rail of the instrument, pedals pivoted to the support beyond the arched portions, bellows, rock 10 shafts, operative connections between the shafts and the respective bellows and operative connections between the pedals and the respective shafts, said pedals being adapted

to be folded into close proximity to the side 15 members and the portions of said side members beyond the arched portions being shaped to form a repository space for the treadles and a portion of the operating mechanism.

20 In testimony whereof I have signed my name to this specification, in the presence of two subscribing witnesses, on this 16th day of Oct. A. D. 1909.

ROBERT J. BENNETT.
